(57) **CLAIM**

The ornamental design for an electric vehicle recharge station, as shown and described.

DESCRIPTION

FIG. 1 is a front elevational view of an electric vehicle recharge station showing my new design;

FIG. 2 is a rear elevational view thereof;

FIG. 3 is a a left-side elevational view thereof;

FIG. 4 is a right-side elevational view thereof;

FIG. 5 is a top plan view thereof, shown enlarged for clarity of detail;

FIG. 6 is a bottom plan view thereof, shown enlarged for clarity of detail; and,

FIG. 7 is a perspective view thereof.

The broken line portion of the figure drawings is included to show unclaimed subject matter and environmental detail only and forms no part of the claimed design.

1 Claim, 4 Drawing Sheets

FIG. 5

FIG. 6

FIG. 7
